UNITED STATES PATENT OFFICE.

PAUL GMEHLIN, OF NEW YORK, N. Y.

KEY-FRAME FOR PIANO-FORTES.

SPECIFICATION forming part of Letters Patent No. 356,759, dated February 1, 1887.

Application filed September 22, 1886. Serial No. 214,216. (No model.)

To all whom it may concern:

Be it known that I, PAUL GMEHLIN, a resident of New York city, in the county and State of New York, have invented an Improvement 5 in Key-Frames for Piano-Fortes, of which the following is a full, clear, and exact description, reference being made to the accompanying drawings, in which—

Figure 1 is a top view of a key-frame of my 10 invention. Fig. 2 is a vertical cross-section on an enlarged scale, the line *c c*, Fig. 1, indicating the plane of section. Fig. 3 is a section on the line *k k*, Fig. 2, said figure being on a still larger scale than Fig. 2. Fig. 4 is an end 15 view of the screw which regulates the position of the key-frame.

The object of this invention is to so construct the key-frame and its connections that the touch of the keys can be regulated at will, and 20 so, also, that any shrinkage of the key-frame or key-bottom can be promptly and conveniently counteracted.

The invention consists, principally, in combining a separate key-frame with a supporting 25 key-bottom and with a special screw, or rather set of screws, for drawing the key-frame into any desired position, as hereinafter described.

In the drawings, the letter *A* represents the key-bottom of a piano-forte, which is usually, 30 or for the purposes of this invention may be, a solid bottom of wood.

B is the key-frame, which is composed of the back rail, *a*, balance-rail, *b*, and front rail, *d*, and of the cross-pieces *e e*. This key-frame *B* 35 is at its back portion, by strong screws or fasteners *f*, secured to the back portion of the key-bottom. Screws *g* may also serve to secure the key-frame, the balance-rail *b*, and the key-bottom *A* together.

C is one of the keys of a piano, and *h* the pin 40 on the balance-rail, which serves as a pivotal connection for said key. The front rail, *d*, of the frame *B* carries the front key-pin, *i*, and a series of puncheons, *j*.

*In the drawings, particularly in Fig. 2, an 45 open space will be observed at *l* between the lower face of the front portion of the key-frame *B* and the upper face of the key-bottom *A*. This open space is left there for the purpose 50 of enabling a set of screws, *D D*, to regulate*

the elevation of the front part of the key-frame *B*, and thereby the height of the puncheons *j* simultaneously—that is to say, the higher these puncheons are placed the shorter will be the stroke of each key *C*. The screws *D* are placed, 55 by preference, in the front portions of the cross-pieces *e* of the key-frame, so that where the key-frame has four such cross-pieces it will have four such screws, *D*. Each of these screws 60 *D* has a threaded shank, *m*, which engages with the wood-work of the key-bottom *A*, as in Fig. 3. The lower end of the screw *D* is squared, as at *n*, or otherwise constructed to be readily gripped by a wrench or a screw-driver. Thus the screw *D* is turned from below 65 to regulate the extent to which its upper portion projects above the key-bottom *A*.

Above the threaded portion *m* the screw *D* has a smooth shank, *o*, which traverses the main part of the key-frame *B*. A loose washer, 70 *p*, rests on the threaded portion *m* and serves as a support for the lower side of the key-frame *B*. A recess, *q*, is cut into the upper face of the key-bottom *A*, for receiving the washer *p* whenever the key-frame is drawn down as far 75 as possible. The uppermost end of the screw *D* is squared, as at *r*, and threaded at its corners. Upon this squared portion *r* is fitted a washer, *s*, having a square hole, so that it cannot turn on the screw, and over this washer is 80 placed a nut, *t*, which engages the threaded corners of the squared portion *r* of the screw. Inasmuch as the washer *s* cannot revolve on the screw, it is not liable to jar the nut *t* loose. For the reception of the washer and nut *s t* a 85 recess, *u*, is formed in the upper face of the key-frame *B*.

In case the key-bottom by warping should spring the key-frame out of shape, and thereby vary the space *l* or the height of the puncheons 90 *j*, it is only necessary to turn the screws *D D* and set the puncheons back to the desired height.

The player can also by the use of this invention give to the keys of his instrument a 95 greater or less degree of motion by adjusting the puncheons *j* to the desired height.

I am aware that adjustable puncheons are old; but they are impracticable, as each has to be adjusted by itself, which renders it impos- 100

sible to secure a uniform touch for a set of keys, and also that a screw has been used for adjusting the balance-rail.

I claim—

- 5 1. In a piano, the combination of the key-bottom A with the key-frame B, secured at one end to said key-bottom, and regulating-screws D, bearing against the other end of said key-frame, all arranged for leaving a space, to l, between the front portion of the key-bottom and key-frame, as specified.
2. The combination of the key-bottom A, and key-frame B, carrying a series of puncheons,

j, with the regulating-screws D, bearing against the front portion of the key-frame for simultaneously adjusting said puncheons, as specified. 15

3. The screw D, having wrench-head n at lower part, threaded portion m, smooth portion o, and squared and threaded upper portion, r, in combination with the washers p s 20 and nut t, for use on the key-bottom A and key-frame B, as herein shown and described.

PAUL GMEHLIN.
